UNITED STATES PATENT OFFICE.

WILLIAM B. PURVIS, OF PHILADELPHIA, PENNSYLVANIA.

ELECTRICAL RAILWAY SYSTEM.

SPECIFICATION forming part of Letters Patent No. 588,176, dated August 17, 1897.

Application filed June 29, 1896. Serial No. 597,333. (No model.)

To all whom it may concern:

Be it known that I, WILLIAM B. PURVIS, a citizen of the United States, residing in the city and county of Philadelphia, State of Pennsylvania, have invented a new and useful Improvement in Electrical Railway Systems, which improvement is fully set forth in the following specification and accompanying drawings.

10 My invention consists of a novel construction of electric railway in which any liability of short-circuiting is reduced to a minimum and provision is made for automatically making electrical connection between the moving car and the concealed or inclosed feed-wire employed, means being further provided for breaking the electrical connection after the car has passed each contact device, all as will be hereinafter set forth, and specifically 15 set out in the claim.

Figure 1 represents a side elevation of an electric railroad embodying my invention, a portion thereof being shown in section. Fig. 2 represents a vertical transverse section on line $x-x$, Fig. 1. Fig. 3 represents a view similar to Fig. 2, but showing slightly-modified construction of contact device. Fig. 4 represents a vertical transverse section showing a modified construction of devices for 20 conducting the electricity from a plurality of auxiliary feed-wires to a single feed-wire.

Similar letters refer to corresponding parts in the several figures.

Referring to the drawings, A designates a 35 car which is provided with the trucks B and the wheels C, having the axles D and the other appurtenances, all of the usual construction.

E designates a yielding or resilient 40 tact-strip of metal, which is attached to a suitable portion of the car, said strip being of course suitably insulated therefrom and having the connection E' therefrom to the car-motor E², from which latter leads the 45 connection E³ to the ground through the medium of the car-axle D or the equivalent elements.

F designates the conduit employed, the same having the top F' and the depending 50 sides F², the conduit thus being open at its bottom, so as to allow the escape of water, moisture, &c., therefrom.

G designates a series of lugs or supports which are attached to the interior of the conduit at suitable intervals for the purpose of 55 sustaining the feeder or conductor H, which is provided with suitable insulation J. K. designates a pin or stationary contact-point which is embedded in said feeder and projects above said insulation and is adapted to 60 contact at suitable intervals, as will be explained, with the adjacent extremity of the pin L or movable contact-point, which is provided with the head M and fits tightly in the diaphragm N, which may be of rubber or 65 other similar resilient material, said diaphragm resting upon the opening or recess P.

In Fig. 3 the construction is substantially the same as that already described, except that a roller or wheel Q is employed upon the 70 pin L in place of the head M, the stationary contact K remaining unchanged.

In Fig. 4 the principle of my invention is the same, the movable contact-pin and the diaphragm remaining unchanged. A plural- 75 ity of auxiliary feed-wires R are employed, which are supported in suitable hangers or brackets attached to the inner walls of the conduit F, said auxiliary feed-wires having conductors leading therefrom to the main conductor or feeder T, which is supported in any 80 suitable manner at the proper distance from the extremity of the pin or movable contact L.

The operation is as follows: The pins or contacts L are placed in their diaphragms at 85 suitable distances apart from each other, which should be less than the length of a car, and the resilient strip E is adjusted so that the said pins L will be depressed when the strip E contacts therewith, as indicated in 90 Fig. 1, during the progress of the car, thereby forming an electrical connection between the movable contacts L and the stationary contacts K or the feeder T, as the case may be. As the car progresses it will be apparent 95 that as the resilient contact-strip E moves away from each head or roller Q the latter will resume the position seen in Figs. 2 to 4, inclusive, by reason of the resiliency of the diaphragm N, the electrical connection being 100 thus effectively broken in every instance after the progression of the car, and it being of course apparent that the electricity is taken from the contact-strip E to the car-motor E².

by the connection E', and thence from the motor to the ground through the medium of the conductor E³.

The operation of the modification seen in Fig. 3 is substantially the same as above described, the roller Q tending to minimize the friction arising from the contact with the strip E.

The operation of the modification seen in Fig. 4 will be apparent without further explanation, the conductor T taking the place of the stationary pins or contacts K.

It will of course be apparent that changes may be made by those skilled in the art which will come within the scope of my invention, and I do not therefore desire to be limited in every instance to the exact construction I have herein shown and described.

Having thus described my invention, what I claim as new, and desire to secure by Letters Patent, is—

A conduit having a series of openings in its top, flexible diaphragms covering said openings, an insulated conductor supported in said conduit, a contact-point secured to and projecting from said conductor, a pin passing through said diaphragms and having its lower end adapted when depressed, to contact with said point, and a movable flexible strip connected with an electric motor and adapted to depress said pin.

WILLIAM B. PURVIS.
